UNITED STATES PATENT OFFICE

165,057

MUFFLER FOR AN EXHAUST GAS SYSTEM

Floyd E. Deremer, Detroit, Mich., assignor to Oldberg Manufacturing Company, Grand Haven, Mich., a corporation of Michigan

Application August 9, 1950, Serial No. 11,681

Term of patent 14 years

(Cl. D14—6)

To all whom it may concern:

Be it known that I, Floyd E. Deremer, a citizen of the United States, residing at Detroit, county of Wayne and State of Michigan, have invented a new, original, and ornamental Design for a Muffler for an Exhaust Gas System, of which the following is a specification, reference being had to the accompanying drawings, forming part hereof.

In the drawing, Figure 1 is a top plan view of a muffler for an exhaust gas system showing my new design;

Figure 2 is an elevational view of the muffler illustrated in Figure 1;

Figure 3 is an end elevational view of the muffler; and

Figure 4 is an isometric view of the muffler.

The characteristic features of the design are shown in full lines.

I claim:

The ornamental design for a muffler for an exhaust gas system, substantially as shown and described.

FLOYD E. DEREMER.
